LATCH FOR PIVOTED LOCKING BOLTS FOR
REPEATING FIREARMS

Val A. Browning, Ogden, Utah

Application April 10, 1948, Serial No. 20,261

5 Claims. (Cl. 89—164)

1

This invention relates to repeating firearms of the recoil operated type wherein the barrel and breech block are locked together by a locking block which, during recoil movement of the barrel, is automatically moved to an unlocking position and which locking block, when the breech block reaches or approaches its normally forward position, is again automatically engaged with the barrel.

An aim of the present invention is to provide a very simple, economical, and efficient arrangement for positively maintaining the locking block in a disengaged position where it will not engage or wipe against the barrel extension during the forward motion of the breech block and which locking block is automatically released so as to move to locking position after the breech block has reached or approximately reached its foremost position.

A further aim of the invention is to provide an improved arrangement wherein that portion of the ejection opening which is not closed by the breech block is closed by a closure member with which is associated the means for latching the locking block in said unlocking position.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

The following description will be more readily understood by referring to the accompanying drawings, in which similar reference numerals refer to similar parts, and in which

Figure 1 is a sectional view taken generally longitudinally and vertically through the firearm with the breech block and other parts shown in side elevation and in firing position, the rear and forward ends of the firearm being omitted;

Fig. 2 is a view similar to Fig. 1 but with the breech block shown in longitudinal, vertical section;

Fig. 3 is a plan view partly in cross section and showing the operating parts in firing position;

Fig. 4 is a view similar to Fig. 3 but illustrating the relative position of the parts when the breech block has reached the end of its recoil movement;

Fig. 5 is a vertical, cross sectional view through the firearm showing the parts in the position of Fig. 4; and

Fig. 6 is a perspective view of the combined

2

latch for the locking block and the closure for the ejection opening.

In the drawings, I have shown, for illustrative purposes, the improvements of the present invention incorporated in a firearm such as is illustrated and described in my Patent No. 2,409,733 granted October 22, 1946, it being understood that such showing is by way of example only and not by way of limitation. Only so much of the firearm is illustrated as is necessary for an understanding of the present invention, it being understood that the firearm will be provided with a cartridge carrier for transferring one or more cartridges in succession up to the barrel extension, and firing mechanism of any suitable type may be provided.

Referring to the drawings in detail, the firearm is shown as having a frame or receiver 10 and a barrel 11, the latter having a barrel extension 12 mounted for reciprocating movement within the receiver. Below the barrel is a guide member 13 which may or may not be in the form of a magazine, this guide member being adapted to guide the forward portion of the barrel in any suitable manner. This guide member may support a recoil spring designated by the numeral 14. Extending downwardly and rearwardly from the rear end of the receiver is a tube 15 within which is mounted a guide member 16 behind which is an action spring 17.

Mounted within the receiver is a breech block 20 which carries the firing pin 21. The breech block has, as is usual, side ribs 22 mounted for sliding movement in longitudinally extending grooves 23 in the inner faces of the receiver. Carried by the breech block is a locking block 24 having a rearwardly facing shoulder 25. The breech block is recessed to accommodate the locking block, the side walls of the recess having arcuate grooves 26 to accommodate like ribs 27 on the sides of the locking block so that the locking block may pivot, in effect, about a point A. The barrel extension has an opening 30 in its upper wall provided at its rear end with a forwardly facing shoulder 31 with which the shoulder 25 on the locking block 24 is adapted to engage, as shown in Fig. 1. The locking block is slotted on its under side so as to accommodate the firing pin and the forward end of a link 32.

The link 32 is pivoted between its ends to the rear lower corner of the locking block as by means of a pin 33. The rear end of the link is pivotally associated with the forward end of the guide piece 16. In the present illustrative disclosure, the link, forwardly of its pivot, has a finger 34 adapted

to cooperate with an upwardly and rearwardly inclined cam surface 35 on the rear face of the forward wall of the breech block, as described more particularly in my said Patent No. 2,409,733. The present invention is not limited to this particular construction as my improvements may be incorporated in repeating firearms wherein unlatching of the locking block is effected in different manners.

When the firearm is fired, the barrel and breech block recoil together and, when the barrel has reached or approximately reached its rearmost position, the locking block is disengaged from the barrel extension, whereupon the breech block and the parts associated therewith continue their recoil movement and then the action spring advances the breech block to its normal forward position, the barrel having been advanced to its forward position by the recoil spring. In accordance with the present invention, I provide an improved, simple, and very effective latch 40 for latching down the locking block during the forward movement of the breech block so as to prevent the locking block from wiping against the barrel extension as the breech block is moving to its closed position within the barrel extension, the locking block being released from the latching member slightly before the breech block arrives at its foremost position. In the present exemplification of the invention, the latching member 40 is shown as being in the form of a slide mounted for longitudinal reciprocation upon the breech block, and a portion of this slide may be employed, as later described, to close, in part, the ejection opening when the breech block is in its breech closing position. It is, of course, obvious that the latching member may take a form other than that particularly here shown.

The latching member 40 is generally U-shaped in plan view, it having a long arm 41 and a shorter arm 42, these arms being in straddling relation to one side wall of the breech block. More particularly, the long arm is located in a longitudinally extending groove 43 in the exterior side face of the breech block, and the other arm is accommodated by a groove 44 on the side face of the recess of the breech block. The connecting portion between these arms is designated by the numeral 45. The long arm 41 is of such length that one end or the other thereof extends beyond the corresponding end of the breech block. The shorter arm 42, which constitutes the locking latch proper, is of such length that, when the slide is in its rearmost position (see Figs. 2 and 3) with respect to the breech block, the arm is free of the locking block and, when the slide is in its foremost position (see Figs. 4 and 5) with respect to the breech block, the forward end of the arm extends over an upwardly facing ledge 46 on the locking block, this ledge being just rearwardly of the locking shoulder 25. The forward end of the long arm 41 is bent inwardly as at 47 so as to lie in front of a shoulder 48 at the forward end of the breech block so that the extent to which the slide may move rearwardly with respect to the breech block is limited. The member 40 is made of spring metal and the arm 41 resiliently bears against the opposing face of the breech block so that there is a drag or friction therebetween to prevent accidental movement of the slide with respect to the breech block.

It will be observed from the drawings that the ejection opening 50 is longer than the breech block in order to facilitate the ejection of the empty shell and, therefore, the breech block does

not provide a complete closure for the ejection opening when the breech block is in firing position. In order to take care of this deficiency, there is associated with the breech block a closure for closing the rear end of the ejection opening. In the present instance, the closure is in the form of a plate or wing 49 depending from the rear end portion of the arm 41. It will be seen from Figs. 1 and 3 that, when the breech block is in its firing position, the closure closes the space between the rear end of the breech block and the rear edge of the ejection opening.

The operation of the gun will be readily understood upon a review of my said patent. It is here sufficient to say that, upon firing a shell in the firing chamber, the breech block, the barrel, and the link, under the pressure of the power gases generated, recoil rearwardly as a unit until the rearward movement of the barrel is about stopped by the recoil spring and its associated parts, whereupon the link, due to its inertia, will continue to move rearwardly thereby disengaging the locking block from the barrel extension. As the recoil spring now returns the barrel to its forward position, the breech block will continue to move rearwardly and, as it approaches its rearmost position, the cross portion 45 of the member 40 will engage the abutment 52 provided at the rear end of the receiver, thus stopping this member slightly before the rearward movement of the breech block is stopped. Thus the member, in effect, is moved forwardly relative to the breech block from the position shown in Fig. 3 to the position shown in Fig. 4. The result is that the forward end of the arm 42 is brought into overlying relation to the ledge 46 of the locking block so that the locking block is latched down in inoperative position. The action spring will now move the breech block forwardly to breech closing position and as, during such movement, the locking block is latched down, it is held against engagement or wiping action against the barrel extension rearwardly of the shoulder 31. As the breech block finally moves to its full breech closing position, the forward end of the arm 41 will engage a shoulder 51 provided at the rear end of the barrel, thus stopping the forward movement of the member 40 slightly before the forward movement of the breech block is stopped, with the result that the ledge 46 of the locking block moves forwardly from beneath the latch arm 42, thus permitting the locking block, under the influence of the action spring, to swing up into locking relation with the barrel extension.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a recoil-operated firearm, a receiver, a barrel mounted for reciprocation on the receiver, a breech block mounted for reciprocation on the receiver, a locking block movably carried by said breech block for movement into and out of locking engagement with said barrel, means for mov-

ing the locking block towards unlocked position upon recoil movement of the barrel, a latching member for holding the said locking block in unlocked position during forward movement of the breech block until the breech block has reached substantially its foremost position, means for stopping rearward movement of said latching member as the breech block approaches its rear-most limit of recoil whereby the latching member is brought into latched position with respect to said locking block, and means for stopping forward movement of said latching member as the breech block approaches its breech closing position whereby the locking block is unlatched.

2. In a recoil-operated firearm, a receiver, a barrel, a breech block, a locking block on the breech block movable into and out of cooperative relationship with the barrel, said barrel and breech block being mounted for reciprocating movement relative to the receiver and said breech block having a longer recoil stroke than said barrel, means for restoring said barrel to its firing position during the interval when the breech block is undergoing its final recoil movement, means for restoring said breech block in cooperative locked relation with the barrel after the barrel has been restored to firing position, a latching member carried by the breech block for latching the locking block in disengaged position during the forward movement of the breech block until substantially the breech block has reached its foremost position, an abutment on the receiver for establishing a latching relationship between the latching member and the locking block as the breech block approaches the rearmost limit of its recoil movement, and means for disengaging the latching member from the locking block as the breech block approaches its full breech closing position.

3. In a recoil-operated firearm, a receiver, a barrel having a barrel extension mounted for reciprocation in the receiver and provided with a locking shoulder, a breech block carried by the receiver and mounted for reciprocation thereon, a locking block carried by said breech block for movement between a locking position and an unlocked position, said locking block having a shoulder arranged to engage said first mentioned shoulder when the breech block is locked to the barrel extension, means for moving said locking block to unlocked position upon recoil movement of the barrel, means for restoring the barrel to its firing position, means for restoring the breech block in cooperative locked relation with the barrel after the barrel has been restored to firing position, and a latch member mounted on said breech block for longitudinal sliding movement relative thereto and constructed and arranged to hold said locking block in unlocked position during forward movement of the breech block until the breech block has substantially reached its foremost position, whereupon the latch member is disengaged from the locking block.

4. In a recoil-operated firearm, a receiver, a barrel having a barrel extension mounted for reciprocation in the receiver and provided with a locking shoulder, a breech block carried by the

receiver and mounted for reciprocation thereon, a locking block carried by said breech block for movement between a locking position and an unlocked position, said locking block having a shoulder arranged to engage said first mentioned shoulder when the breech block is locked to the barrel extension, means for moving said locking block to unlocked position upon recoil movement of the barrel, means for restoring the barrel to its firing position, means for restoring the breech block in cooperative locked relation with the barrel after the barrel has been restored to firing position, and a latch member carried by said breech block for sliding longitudinal movement relative thereto and having a forward position with respect to the breech block in which the latch member maintains said locking block in unlocked position during the forward movement of the breech block until the breech block has substantially reached its foremost position, said latch member in its rearmost position with respect to the breech block being in inoperative position, a shoulder for stopping the rearward movement of the latch member and then the rearward movement of the breech block whereby the latch member is engaged with the locking block as the breech block approaches its rear-most limit of recoil movement, and a shoulder against which said latch member engages as the breech block approaches its full breech closing position whereby said latch member is disengaged from the locking block.

5. In a recoil-operated firearm, a receiver having an ejection opening, a barrel mounted for reciprocation on the receiver, a breech block mounted for reciprocation on said receiver and of lesser length than the length of said ejection opening, a locking block movably carried by said breech block for movement into and out of locking engagement with said barrel, means for moving the locking block towards unlocked position upon recoil movement of the barrel, a latching member for holding said locking block in unlocked position during forward movement of the breech block until the breech block has reached substantially its foremost position, means for stopping rearward movement of the latching member as the breech block approaches its rear-most movement of recoil whereby the latching member is brought into latched position with respect to said locking block, and means for stopping forward movement of the latching member as the breech block approaches its breech closing position whereby the locking block is unlatched, said latching member having a plate portion adapted to close the rear end of said ejection opening when the breech block is in breech closing position.
